COTTON CLEANER

Lucien L. McDaniel and Frank E. Deems, Birmingham, Ala., assignors to Continental Gin Company, a corporation of Delaware

Application July 31, 1944, Serial No. 547,371

7 Claims.

(Cl. 19—93)

This invention relates to cotton cleaners and has for an object the provision of an apparatus and method for cleaning cotton in which the cotton is subjected to a beating action in which it is tossed to and fro between cleaning elements so disposed as to provide a screen for removing dirt and trash.

A further object of our invention is to provide a cotton cleaner embodying upper and lower rows of cylinders having agitating and cleaning elements thereon, the cylinders being so disposed that the cotton introduced into the cleaner is carried over the upper series of cylinders and then over the lower series of cylinders, to be there acted upon by both cylinders, the cylinders being provided with agitating and cleaning elements so spaced as to form screens.

A still further object of our invention is to provide a cotton cleaner which shall be simple of design, economical of manufacture, and which shall be adapted to operate without clogging or choking due to large wads of cotton becoming wedged therein.

Cotton cleaning mechanism as heretofore known to us has usually embodied screens of various types, together with rollers having vanes or spikes thereon for conveying the cotton thereover. Cleaning is accomplished by drawing the cotton over the screens in a direction approximately parallel to the screen surface, thus wiping or scrubbing the cotton over the screens and often embedding dirt and trash in the cotton that would otherwise be separated. Difficulties have also been encountered in designing the screens for use in such cleaning apparatus. If the mesh of the screen be too large, the seed cotton will be discharged with the trash, and when the mesh is small enough to retain the cotton, the dirt and trash do not readily pass. Furthermore, all screens of the type heretofore employed have a tendency to "hair over" from loose fibers or other materials and thus become clogged. Foreign material, such as stone or iron which accidentally get into the seed cotton sometimes damage and break the screen. Also, complete choking of a cleaner unit due to large wads of cotton wedging between the screens and the rollers is a frequent source of trouble.

These and other difficulties are overcome by our invention in which the screen surface is replaced by a series of rotating cylinders having agitating and cleaning elements thereon spaced to provide the maximum opening for dirt and trash, but close enough to provide a screen for the cotton. Preferably, we provide an upper and a

lower series of cylinders mounted in a casing and so disposed that the cotton is passed first over the upper surface of the upper series of cylinders and then over the upper surface of the lower series of cylinders. The two series of cylinders are so disposed with respect to each other, that the cotton in passing over the lower series is tossed to and fro between the upper and lower series, thus subjecting it to a beating action in which the cotton is maintained in an open, fluffy condition. Dirt and trash are thus effectively removed from the cotton, falling between the agitating and cleaning elements on the lower series of cylinders. No choking of the apparatus is possible, because all of the cylinders rotate in a direction to propel the cotton from the inlet to the discharge outlet of the apparatus.

Apparatus embodying features of our invention is illustrated in the accompanying drawings forming a part of this application, in which

Fig. 1 is a sectional elevation showing one form of our improved apparatus;

Fig. 2 is a sectional view taken along the line II—II of Fig. 1;

Fig. 3 is a fragmentary sectional plan view showing the arrangement of the agitating and the cleaning elements on a pair of the lower series of cylinders;

Fig. 4 is a fragmentary sectional view similar to Fig. 3, showing a modified arrangement;

Fig. 5 is a sectional elevation similar to Fig. 1, showing a modified form of our invention;

Fig. 6 is a sectional view taken along the line VI—VI of Fig. 5; and

Fig. 7 is a fragmentary plan view of a cylinder showing the arrangement of the cleaning elements on the cylinders illustrated in Figs. 5 and 6.

Referring now to Figs. 1 to 4 of the drawings, our improved apparatus embodies an elongated casing 10 having an inlet opening 11 and a material outlet opening 12. Cotton may be fed into the opening 11 by means of a feeder 13. Mounted in the upper portion of the casing 10 is an upper series of cleaning cylinders 14. The cylinders 14 are arranged in horizontal, parallel, side by side relation, and each cylinder is provided with a plurality of agitating and cleaning elements 16. As shown in Fig. 2, the agitating and cleaning elements 16 may consist of vanes, and the cylinders 14 are so spaced laterally that, in cooperation with the vanes 16, the space between the cylinders is substantially closed and cotton does not fall down between the cylinders. Small dirt and trash, however, can freely pass downwardly between the cylinders and thus be

removed from the cotton. The cylinders 14 are all rapidly rotated by any suitable means, not shown, in the direction shown by the arrows in Fig. 1, so that cotton falling on the first of the cylinders in the series is carried over the top of the series to the opposite end of the casing. Disposed at the opposite end of the casing, in the path of the cotton delivered from the last of the cylinders 14 of the series, is a screen 17 which acts as a baffle against which the cotton is forcibly thrown and directed downwardly on to the lower series of cylinders. Some dirt and trash will pass through the screens 17 and be removed from the cotton at this point.

Mounted in the casing 10 immediately below the upper series of cylinders 14, is a lower series of cylinders 18, corresponding in number to the upper series and, in accordance with the modification shown in Fig. 1, with each cylinder of the lower series disposed immediately below a corresponding cylinder in the upper series 14. The first cylinder of the series 18, considered in the direction of movement of the cotton through the cleaner, is positioned to receive the cotton, falling downwardly from the screen 17. The cylinders of the lower series 18 are provided with agitating and cleaning elements which, in the form shown in this modification, consist of serrated disks 19. All of the cylinders of the lower series are rotated at a relatively high rate of speed by any suitable means, not shown, in a direction opposite to the direction of rotation of the upper series of cylinders 14. The lower series of cylinders 18, being disposed immediately below the upper series 14, the agitating and cleaning elements 19 engage the cotton and toss it upwardly against the upper series of cylinders where it is met by the elements 16 and tossed back again against the lower series of cylinders, thus subjecting the cotton to a violent beating action. This effectively knocks the dirt and trash out of the cotton, allowing it to pass downwardly between the disks 19, into a hopper 21 in the bottom of the casing, from whence it may be removed by any suitable mechanism, not shown. It will be seen by this action, the cotton is maintained in an open, fluffy condition, and that due to the rapid rotation of the cylinders, there is no possibility of clogging the cleaning elements.

In Fig. 3 of the drawings, we show in detail one method of mounting the disks 19. In accordance with this modification, the disks 19 are mounted on shafts 22 with suitable spacers 23 between the disks and with the disks on one shaft extending between the disks on an adjacent shaft, whereby uniform openings 24 are provided between the cylinders for the passage of dirt and trash.

In Fig. 4 of the drawings, we show a modified form of mounting for the disks. In accordance with this modification, we show disks 26 mounted on shafts 27 and spaced apart by means of spacers 28. The disks on adjacent shafts, in accordance with this modification, are evenly spaced and directly opposed, the distance between edges of disks on adjacent shafts being substantially the same as the distance between disks on the same shaft. By means of this construction, we can employ spacer blocks 28 which occupy less space than those shown in Fig. 3, and thus provide a greater area of opening between the disks than between the disks 19.

Referring now to Fig. 5 of the drawings, we show a modified form of our invention which includes a casing 10', similar to the casing 10 and having an inlet opening 11', and a discharge

opening 12'. Mounted in the upper part of the casing 10' is an upper series of cylinders 29 arranged in horizontal, parallel, side by side relation, similar to the series of cylinders 14 shown in Fig. 1. Disposed beneath the series of cylinders 29, is a lower series of cylinders 31. Instead of the cylinders of the lower series being disposed directly beneath the corresponding cylinders in the upper series 29, the cylinders of the series 31 are disposed immediately beneath the space between corresponding cylinders in the upper series 29.

The cylinders of the upper series 29 are all rotated rapidly in the same direction similar to the series 14 in Fig. 1, and the cylinders in the lower series 31 are likewise rotated in the same direction, but opposite to the direction of rotation of the cylinders in the series 29. Cotton is delivered to the upper series of cylinders 29 through the inlet opening 11' and is carried over the upper cylinders and thrown against the screen 17' to fall downwardly therefrom onto the lower series of cylinders 31, and is then carried over the lower series and delivered outwardly through the discharge outlet 12'.

25 In accordance with this modification of our invention, we provide the cylinders in the series 29 and 31 with agitating and cleaning elements in the form of spikes 32 which are so spaced on the cylinders and the cylinders are so spaced with respect to each other as to form a screen for the cotton, permitting the dirt and trash to fall downwardly between the spikes and the cylinders. The rows of spikes 32, as shown in Fig. 7, are preferably so arranged that the spikes in one row 30 are in staggered relation with respect to the spikes on adjacent rows. There is thus provided an efficient screen for the cotton with ample space between the spikes for the passage of dirt and trash.

40 With the arrangement shown in Figs. 5 to 7 inclusive, the cotton is subjected to a violent beating action and is tossed back and forth between the upper and lower series of cylinders as indicated by the arrows to fluff it and free it from dirt 45 and trash before it is discharged through the outlet 12'.

From the foregoing it will be apparent that we have devised an improved cotton cleaning apparatus which is simple of design and operation and 50 which is adapted to remove dirt and trash from the cotton without any wadding or roping of the cotton, and without the possibility of choking the apparatus. It will also be apparent that our apparatus is especially adapted, if desired, for the 55 circulation of heated air through the casing so that the cotton may be simultaneously dried and cleaned, in a manner well understood in the art. For this purpose, we show the vacuum feeder 13' in Fig. 5 connected to the outlet 12' and show an 60 outlet 33 through which heated moist air may be withdrawn from the casing. In such an arrangement, the cotton along with heated air may be admitted through an inlet 11', and the circulation of air through the casing aids in 65 cleaning the cotton. Such arrangements are well known in other forms of cleaning and drying apparatus and need no detail description.

While we have shown our invention in but two forms, it will be obvious to those skilled in 70 the art that it is not so limited, but is susceptible of various other changes and modifications, without departing from the spirit thereof, and we desire, therefore, that only such limitations shall be placed thereupon as are specifically set forth 75 in the appended claims.

What we claim is:

1. In a cotton cleaner, an upper series of rotary cylinders disposed in parallel, side by side relation, beater elements on the cylinders, a lower series of cylinders parallel to the upper series and disposed beneath the upper series in position to receive cotton therefrom, agitating elements on the lower series of cylinders spaced to permit the passage of dirt and trash therebetween but close enough to prevent the passage of cotton, the respective series being so disposed as to provide a vertical space between the elements thereon, means to feed cotton onto one end of the upper series, and means to drive the cylinders in a direction for the cotton to be carried first over the upper series and then over the lower series, and to be tossed from the lower series upwardly against the upper series and back against the lower series.

2. A cotton cleaner comprising upper and lower substantially horizontal series of rotary cylinders, the cylinders in each series being disposed in closely spaced relation, agitating elements on both series of cylinders, the elements on the lower series being spaced to provide a screen for the passage of dirt and trash therebetween, means to feed cotton on to one end of the upper series of cylinders, baffle means opposite the other end of said upper series disposed to receive cotton from said series and to deliver it to the lower series, means to drive the upper series of cylinders in a direction to carry the cotton from end to end thereof and discharge it against the baffle means, and means to drive the lower series in a direction for the agitating elements to throw the cotton upwardly against the elements of the upper series and to carry it to the opposite end of the lower series and deliver it from the cleaner.

3. In a cotton cleaner, a casing having a feed opening in the top near one end thereof and a delivery opening below the feed opening, an upper series of cylinders mounted in the casing in parallel side by side relation, the first of the series being mounted beneath the feed opening, beater elements on the cylinders, means to rotate the cylinders in a direction to carry the cotton along the upper surfaces thereof, a substantially vertically disposed screen in the casing disposed to receive cotton from the upper series of cylinders, a lower series of cylinders mounted in

the casing in parallel, side by side relation beneath the upper series and disposed to receive cotton falling downwardly from the screen, agitating elements mounted on the lower cylinder and spaced to provide a screen for the cotton through which trash and dirt may pass, and means to drive the lower series in a direction to carry the cotton from one end to the other of the series and to toss it upwardly against the upper series and to deliver it through the delivery opening of the casing.

4. In a cotton cleaner, a lower row of horizontally disposed rotary cylinders having agitating elements thereon, an upper similar row of cylinders parallel to the lower row with the agitating elements of one row vertically spaced with respect to the elements on the other row, means to drive the respective rows of cylinders in opposite directions whereby to toss the cotton upwardly and downwardly, back and forth, between the rows as they are rotated, the elements on the lower row being closely spaced to form a screen.

5. Apparatus as defined in claim 4 in which the agitating elements on the lower row of cylinders consist of serrated disks spaced on the cylinder to form elements of a screen, and the adjacent cylinders in a row are disposed with their respective disks spaced to form a screen.

6. Apparatus as defined in claim 4 in which the agitating elements consist of rows of spikes mounted on the cylinders and spaced to form a screen, and in which adjacent cylinders in a row are disposed with their respective spikes spaced to form the screen.

7. A cotton cleaner comprising parallel horizontally disposed upper and lower series of rotary cylinders, agitating and cleaning elements on the cylinders, the elements on the lower series being closely enough spaced to form a screen, and the arrangement being such as to provide a vertical space between the elements of the two series, means to feed cotton into the cleaner to pass between the series, and means to drive the upper series of cylinders in one direction and the lower series in another whereby the cotton is tossed upwardly and downwardly, back and forth, between the upper and lower series in its passage.
